UNITED STATES PATENT OFFICE.

SHELDON LEICESTER, OF LONDON, ENGLAND.

TRANSFER FOR PRINTING ON POTTERY AND ENAMEL WARE.

1,175,779.

Specification of Letters Patent. Patented Mar. 14, 1916.

No Drawing.

Application filed November 21, 1914. Serial No. 873,416.

To all whom it may concern:

Be it known that I, SHELDON LEICESTER, a British subject, residing at London, England, have invented certain new and useful 5 Improvements in and Relating to Transfers for Printing on Pottery and Enamel Ware, of which the following is a specification.

This invention relates to the preparation or manufacture of transfers for printing 10 upon ceramic ware and vitreous porcelain or other enamel surfaces, such as decoration of pottery, stained glass and enameled metallic signs. Such transfers are at present prepared or printed by an ordinary 15 lithographic process whereby the designs are drawn on stone or metal plates or engraved on plates mechanically or by hand; in the latter case an impression being taken from the engraved plate and placed on the 20 stone or printing plate. This method necessitates a separate drawing for each piece of a set (such as dinner or tea service) of different size. From the stone the design is 25 printed upon paper prepared with gum or dextrin for conveyance and on being wetted adheres to the pottery, the colors which are inorganic pigments being burnt into the ware during firing.

By this invention a photographic negative 30 is made of the design, drawing, picture or subject taken direct from nature and a positive on glass or film taken from the negative; this positive is photographed on to carbon tissue sensitized paper, and the latter 35 squeezed down onto a burnished metal surface such as a copper cylinder or plate. This is developed in hot water on the surface of the copper by immersing the cylinder and subsequently painting out the margins with 40 an iron per-chlorid (or other etching medium) varnish resist, and the design is finally etched thereon in relief.

A screen is used in printing the carbon transfer, or it can also be used when making 45 the negative or positive. This acts as a pocket of varying depth to hold the right amount of ink to give the right shade on the plate. The thinnest parts of the carbon print represent the heavy shades, and the 50 thickest parts the lightest shades, so that the various shades are procured by the various thicknesses of the carbon, hence the etching fluid percolates through the carbon and etches the copper exactly in the 55 gradations of the shade of the design photographically.

The copper cylinder or plate containing the engraving is placed on a printing machine provided with arrangements for supplying ink to the engraved surfaces, and 60 also provided with a doctor knife which removes the superfluous ink and regulates the amount of ink retained in the engraving. The paper which is gum or dextrin coated is sheet or reel fed. The design may be 65 similarly developed from a carbon print direct upon a plate and printed on a flat bed photogravure printing machine. The cylinders or plates employed may be copper or steel or other metal either solid or deposited. The colors used will be pigment or 70 mineral colors, such as now used in the decoration of pottery or glass, which will stand the firing process required for pottery or enamel ware.

By this invention I am enabled to produce 75 ceramic transfers by direct intaglio printing, that is direct from an engraved or etched copper steel or other metal cylinder or plate so that the pigment lies in relief on the surface of the transfer. The enlargement, reduction and reproduction of designs being 80 entirely photographic will be much cheaper and more accurate than the old method and the range of pictorial photographic designs 85 will be much greater.

The invention is also applicable for producing transfers for glass ware and vitreous or other enamel ware such as enameled iron plates for advertising or other purposes. 90

What I claim as my invention and desire to protect by Letters Patent is:—

1. The process for preparing transfers for printing upon pottery and enamel ware which consists in preparing a photographic 95 negative of the design direct from the drawing, picture or subject, obtaining a positive therefrom on glass or transparent film, photographing or printing onto a carbon tissue sensitized paper from the positive, affixing the latter onto a burnished metal 100 surface developing same onto the metal surface, etching the same into the metal surface in intaglio to receive the printing ink and finally printing the design therefrom 105 in relief upon adhesive coated paper in an ink of mineral color suitable for ornamenting pottery or other ware substantially as described.

2. The process for preparing transfers for 110 printing upon pottery and enamel ware, which consists in preparing a photographic

- negative of the design direct from the drawing, picture or subject, obtaining a positive therefrom on glass or transparent film, photographing or printing onto a carbon tissue sensitized paper from the positive, affixing the latter onto a burnished cylinder or plate of copper or other metal, developing same onto the metal surface, etching the same into the metal surface in intaglio to 5 receive the printing ink and finally printing the design therefrom in relief upon dextrin 10

or gum coated paper in an ink of mineral color suitable for ornamenting pottery and other ware substantially as described.

In testimony whereof I have hereunto set 15 my hand in presence of two subscribing witnesses.

SHELDON LEICESTER.

Witnesses:

JAMES S. INGRAM,
J. P. HOWARD.
